LAMP.

1,171,820.

Specification of Letters Patent. Patented Feb. 15, 1916.

Application filed July 26, 1915. Serial No. 42,024.

To all whom it may concern:

Be it known that we, WILLIAM A. WATKINS and AUSTIN A. GAMBLE, both citizens of the United States, residing at Riverside, 5 in the county of Riverside and State of California, have jointly invented new and useful Improvements in Lamps, of which the following is a specification.

This invention relates to lamps, and more 10 particularly to lamps and headlights, such as are employed on motor vehicles and locomotives for illuminating the road or track ahead of the vehicle or locomotive. For the purpose of such illumination high-powered 15 lamps are employed, rendering the roadway or right of way visible for a long distance ahead, not for the particular purpose of advertising the approach of the vehicle or locomotive, but more particularly for showing 20 up any obstacles or obstructions to progress, so as to prevent accident alike to vehicle or locomotive or its train, or injury or destruction of life or property incident to collisions. Such high-powered lamps are 25 for these purposes necessary in order that the high speed of such vehicles or locomotives may be checked where necessary to prevent destruction by collision, and to that end to afford a proper time limit for the purpose 30 of so checking the speed or bringing the vehicle or locomotive to a stop. Incident to the use of such high-powered lamps is the blinding glare produced thereby and interfering with the sight of pedestrians and 35 drivers upon or crossing the roadway or right of way along which such rays are projected. Such interference in itself tends to accident and disaster, tending to produce an 40 improper conception of the location upon the roadway or distance away of the approaching vehicle or locomotive. The use of such lamps with unmodified projected rays thus becomes a menace to the use of the roadway or crossing of the right of way, and 45 tends often rather to invite disaster than to prevent it. This is particularly the case when such lamps are employed by mutually 50 approaching automobiles, and frequent collisions have occurred due to the blinding effect of the projected rays of such lamps. Attempts have been made to remedy these objectionable features of the use of such high-powered lamps, but frequently the result

has been that the power of the lamp has been diminished so that the performance of its 55 principal functions has been defeated.

It is the object of the present invention to provide an improved lamp of the general character stated which will serve effectively to apprise pedestrians, drivers and others of 60 the approach of vehicles or locomotives or cars or the like equipped with the same, which will likewise sharply and clearly define the roadway or right of way and any objects or obstacles thereupon ahead of the vehicle, and which at the same time will not 65 emit such direct or unmodified rays as will produce the objectionable blinding effects above pointed out.

The invention has for further objects the 70 production of an improved lamp of the general character stated which will be superior in point of relative simplicity of construction, inexpensiveness of organization, facility 75 of attachment, convenience of use, compactness of form, and positiveness in action and performance of service, and will be generally superior in efficiency and serviceability.

With the above and other objects in view, the invention consists in the novel and useful provision, formation, construction, combination, association and relative arrangement of parts, members and features, all as hereinafter described, shown in the drawing 80 and finally pointed out in claims.

In the drawings: Figure 1 is a front elevation of a lamp constructed and organized in accordance with the invention, parts being broken away for clearness of illustration; Fig. 2 is a vertical central sectional 90 view of the same; Fig. 3 is an inner face view of the ray-modifying means shown in the other figures, the same being shown in detached position for clearness of illustration.

Corresponding parts in all the figures are designated by the same reference characters.

Referring to the drawings the element A, which is a reverse reflector having an opposed relation to the main reflector, is disclosed as mounted upon a frame 9, arranged within the aperture of the lamp and preferably comprising a major segmental metallic rim joined with the extremities of which is a transverse element or minor segmental metallic rim 10, to which is applied

a sheet or plate 11 of glass or other transparent or translucent material, being shown in the drawing as ground glass.

The element A consists of a preferably metallic segment 12 connected at its lower margin with and conforming in contour with the segmental rim 10, and merging upwardly and inwardly of or away from the glass 11, which latter is held in place behind such segment or disk 12 and between the rim 9 and a flange 9^a upon the same. The rim 9 is held in place in the annular frame 13 of the transparent or translucent face 14 of the lamp C by screws or other holding devices 15 passed through an annulus 16 against the rim 9. It will be understood that the annular frame 13 is hinged to the body 17 of the lamp, as at 18, and provided with securing or fastening means 19 whereby the frame with the disk 12, glasses 11 and 14 and rims 9 and 10 may be opened or shut jointly as a door or closure for the aperture of the lamp. Within the lamp body, which is of the usual or any preferred form, is mounted a parabolic or other suitable reflector 20 and the lamp B, which reflector tends to project the rays emanated from the lamp forwardly through the glass 14 and the glass 11, which glass 11 and the rims 9 and 10 and the plate 12 are disposed in the path of the rays of the light beam directed from the reflector 20. The direct forwardly projected rays of such beam are interrupted by the plate 12 which is a reflector in nature and which directs the rays which impinge upon it rearwardly and downwardly so that they are ultimately projected subsequent to further deflection forwardly and through the glasses 11 and 14, around the reflecting plate 12, which, as stated, obstructs the direct forward projection of the rays which impinge upon it.

From the above description taken in connection with the accompanying drawings, and the following statement, it will be obvious that in the form of construction shown the light rays are in the main projected forwardly and downwardly so as to escape from the lamp beneath the preferably translucent or ground glass 11 and the opaque reflector plate 12. It will be understood that the rims 9 and 10 are also of opaque material. The direct glare from the lamp B is masked and the rays which would otherwise tend to blind eyes directed in vision toward it are modified by the ground glass 11 or reflected by the plate 12 and subsequently reflected by the reflector 20 so as to be eventually projected from the lamp through the ground glass 11 or the transparent glass 14 beneath the reflector plate 12. This reflector plate 12, arranged substantially in the plane of the aperture, thus acts as a shield to the vision and likewise tends to direct the rays out of direct projection from the lamp so

that they may be utilized upon further re-projection. The rays directed from the lamp above the path of direct forward re-projection are modified and softened or lessened in intensity by the ground glass 11. 70 The lamp thus effectively illuminates the forward roadway or right of way without producing the glare which tends to confuse or result in the injury and damage of persons or property; and the lamp is found to be 75 highly efficient for all the purposes required of it, with the saving qualities just mentioned.

By use of the features of lamp and head-light improvement constituting the invention, we are enabled to introduce a considerable safety factor as affecting drivers of vehicles and pedestrians, and at the same time provide for such proper illumination of the roadway as is necessary for the safe 85 operation of vehicles, locomotives and the like.

It is manifest that the rims 9 and 10 may have their rearwardly facing portions constituted as reflecting surfaces if desired. 90

It is manifest that many changes may be made in the provision, construction, formation, combination, association and relative arrangement of parts, members and features, or with reference to the foregoing description and statement and the accompanying drawings, without departing from the spirit of the invention and a fair interpretation thereof.

Having thus disclosed our invention, we 100 claim and desire to secure by Letters Patent:

1. A lamp having an aperture in the face thereof and provided with a main reflector for projecting light rays through the aperture, a reverse reflector having an opposed relation to the main reflector and arranged substantially in the plane of the aperture and spaced from the edges thereof, a translucent plate across the area between the reverse reflector and one side of the aperture, and a transparent plate across the area between the reverse reflector and the other side of the aperture. 110

2. A lamp having an aperture in the face thereof and provided with a main reflector for projecting light rays through the aperture, a reverse reflector having an opposed relation to the main reflector and arranged substantially in the plane of the aperture 120 and spaced from the edges thereof, an opaque rim projecting into the aperture on one side thereof, a translucent plate across the area between the opaque rim and the reverse reflector, and a transparent plate 125 across the area between the reverse reflector and the opposite side of the aperture.

3. A lamp having an aperture in the face thereof and provided with a main reflector for projecting light rays through the aper- 130

ture, a reverse reflector having an opposed relation to the main reflector and arranged substantially in the plane of the aperture and spaced from the edges thereof, said reverse reflector being inclined at an angle to the plane of the aperture, a translucent plate across the area between the reverse reflector and one side of the aperture, and a transparent plate across the area between the reverse reflector and the opposite side of the aperture.

4. A lamp having an aperture in the face thereof and provided with a main reflector for projecting rays through the aperture, a frame fitted within the aperture and including an opaque peripheral rim projecting into the aperture at one side thereof and a transverse element extending across the aperture, a translucent plate extending across the area defined by the frame, a reverse reflector carried by the transverse element and having an opposed relation to the main reflector, and a transparent plate across the area between the frame and the opposite side of the aperture.

5. A lamp having an aperture in the face thereof and provided with a main reflector for projecting light rays through the aperture, a frame arranged within the aperture, and including an opaque peripheral rim projecting into the aperture from one side thereof and a transverse element extending

across the aperture, a translucent plate extending across the area defined by the frame, a reverse reflector carried by the transverse element of the frame and having an opposed relation to the main reflector, said reverse reflector projecting inwardly at an angle to the plane of the frame, and a transparent plate across the area between the frame and the opposite side of the aperture.

6. A lamp having an aperture in the face thereof and provided with a main reflector for projecting light rays through the aperture, and a reverse reflector having an opposed relation to the main reflector and arranged substantially in the plane of the aperture and spaced from the edges thereof, said reverse reflector being disposed at an angle to the plane of the aperture so that the major portion of the reversely reflected light rays will be reprojected through the aperture on one side of the reverse reflector.

In testimony whereof, we have signed our names to this specification in the presence of two subscribing witnesses.

WILLIAM A. WATKINS
AUSTIN A. GAMBLE.
